US00D587671S

(12) **United States Design Patent**
Park et al.

(10) **Patent No.:** **US D587,671 S**
(45) **Date of Patent:** **** Mar. 3, 2009**

(54) **CELLULAR PHONE**

(75) Inventors: **Jun-Sang Park**, Gyeonggi-do (KR);
Seung-Min Park, Seoul (KR);
Chang-Hwan Hwang, Gyeonggi-do (KR)

(73) Assignee: **Samsung Electronics Co., Ltd.**, Suwon-Si (KR)

(**) Term: **14 Years**

(21) Appl. No.: **29/300,488**

(22) Filed: **Apr. 1, 2008**

(51) **LOC (9) Cl.** **14-03**

(52) **U.S. Cl.** **D14/138 AD**

(58) **Field of Classification Search** **D14/137, D14/138 R, 138 AA, 138 AB, 138 AC, 138 AD, D14/138 C, 138 G, 147, 191, 218, 247-248, D14/341-347, 496; D10/65, 78, 104; D13/168; D18/7; 455/556.1, 566, 575.1, 575.3; 345/169**
See application file for complete search history.

(57) **CLAIM**

The ornamental design for a cellular phone, as shown and described.

DESCRIPTION

FIG. 1 is a perspective view of a cellular phone according to our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the cellular phone according to our new design in a state in which the cellular phone is open when used.

1 Claim, 6 Drawing Sheets
